JEWELRY MEDALLION

Julian Harold Kushner, 19 Westwood Circle,
Roslyn Heights, N.Y.

Filed Apr. 4, 1962, Ser. No. 69,577

Term of patent 7 years

(Cl. D45—1)

FIG. 1 is a front elevational view of a jewelry medallion, showing my new design; and

FIG. 2 is a side elevational view thereof, the opposite side being substantially a mirror image thereof.

I claim:

The ornamental design for a jewelry medallion, as shown and described.
